INVENTOR

Tandy B. Thurman.
BY Arthur Brown

A. ORNEY

UNITED STATES PATENT OFFICE.

TANDY B. THURMAN, OF KANSAS CITY, MISSOURI, ASSIGNOR TO THE ARTCRAFT COMPANY, A COMMON-LAW TRUST, COMPOSED OF TANDY B. THURMAN, MILDRED THURMAN, AND LENA JOY THURMAN.

HINGE.

Application filed November 22, 1926. Serial No. 149,942.

My invention relates to hinges and more particularly to hinges of a latching type.

My object is to provide a hinge whereby a swinging member may be conveniently positioned and removed and particularly having novel and improved features for latching a closure in an adjusted position from which position it may be easily retracted.

Another object is to provide a hinge, having a minimum of parts, of low cost, substantial and not liable to damage or disorder, of simple design and easy to produce.

A further object is to provide a device that having a principal use as a hinge may also be adapted for use as a supplementary latch hinge, and as a door stop.

In accomplishing these objects I have been able to dispense with the usual latches and ratchets employed to gain similar ends and have provided a pair of wires coils, the one adapted to rotative insertion into the other; that is, the exterior spiral of the one engaging and threading the interior spiral groove of the other, considering them as screw threaded elements. The inserted coil is of course of less diameter than the socket coil and in some of my uses preferably cone-shaped so that continued rotation in the receiver causes the device to act as a cone clutch. One of the coils is to be attached to the closure member and the other to the casing of a window or door or the like.

The device is susceptible of various adaptations both in the manner of application to the closure and casing and in adjustment of the coils to each other. I show as a preferable form the coil of larger diameter serving as the butt element of a hinge and being the socket for the reception of a companion coil or pin member that is attached to the screen. The resilient engagement of the two produce a holding hinge that sustains a screen in any position. Obviously the device may be used as a supplementary hinge or stopping element on a vertically hinged door. In another form, the pin member is cone-shaped, and clutches the socket member upon rotation, being released by reverse rotation. The relations of the coils may be reversed, the socket being held by the closure. The relative directions of coiling the wires constituting the springs may be adapted to

the functioning of a cone clutch factor upon the retraction of the closure, the hinge in such case offering resistance to closure and so constituting a means of preventing the slamming of the closure. Other adjustments will suggest themselves to a person skilled in the art, and I wish it understood that such variations in the use of the principal elements that I offer shall be considered as coming within the application of my invention. For convenience I have selected certain forms to be described, reference being had to the accompanying drawings in which:

Fig. 1 is a perspective view of the upper portion of a window and window screen, illustrating an embodiment of my invention.

Fig. 2 is a detail perspective view of parts of a hinge in spaced relation.

Fig. 3 is a sectional view taken longitudinally through the hinge shown in Fig. 2.

Fig. 4 is a modified form of a hinge in functional position.

Fig. 5 is an enlarged vertical sectional view through the modified form shown in Fig. 4.

Referring more in detail to the drawings: 1 designates a screen, 2 a window casing with which the hinge is associated, and 3 a keeper bracket secured to the casing and having a flat hook portion 4, the bracket having a comparatively elongated flat socket for the reception of the hinge as will later be described. There are two brackets on the casing. The hinges are preferably identical in structure, though they may be of opposite type. One will be described. A hinge consists of two elements, one a socket member 5 comprising a coil 6 having an exterior end 7 and an arm 8 preferably constructed by bending of an end of the wire radially of the coil to form an elbow 9 and turning the wire and flattening it to form the arm 8. The arm is intended to support the coil by the engagement with the hook of the keeper bracket 3.

The second element of the hinge, which may be referred to as the pin member, is designated 10 and comprises a coil 11 of maximum diameter less than that of the socket member by substantially half of the diameter of the socket coil wire. The coil

11 of the pin member may be cone-shaped, as indicated in Figs. 4 and 5, where the extremity 12 is of less diameter than the end 13 whereby a substantial part of the pin member is easily inserted into the socket member; and whereby rotations of the pin member in the socket member, after initial insertion, cause cone clutch engagement. The wire of which the cone is constructed is 10 bent at 14' and flattened to form a plate 15' to be received in a bracket 17 hereinafter described.

In applying my device to a window casting and screen the brackets are installed on 15 the casing. The pin member is attached to the screen, the socket member is engaged with the pin member and rotated thereon until a substantial part of the pin member is embraced therein. The members are so 20 adjusted by manufacture and manipulation that upon juxtaposing the screen to the casing, the arm 8 of the socket member may seat in the keeper bracket 3. The screen may be opened by pushing out its free end, 25 the pin member rotating in the socket member in spiral travel by reason of the engagement of its exterior thread-like rounds with the inner walls of the rounds of the socket member, and the resiliency of the rounds of 30 the two members provides an additional spring factor whereby the screen may be pushed out to any desired degree of openness; and the clutch will hold it in any position where it may be released. Upon re- 35 tracting of the screen the pin member coil is rotated reversely, the coiled engagement latching the closure yieldingly against accidental opening.

The device may be applied to a door or 40 window otherwise hinged, in which case a single hinge of my design may serve the purpose of a stop-latch or brake, and may be used in association with a retraction spring that is integral with my device or 45 entirely distinct therefrom. The identical form of hinge shown in Figs. 1 and 2 heretofore described, is used for the supplemental hinge purpose, though a different method of attachment to door or casing may 50 be employed, to overcome the vertical displacement factor arising from the travel of the pin element into the socket member. In order to avoid placing the strain of such displacement upon the spring member, I 55 provide for the vertically slidable positioning of the hinge in its casing bracket. I show such modification in Figs. 4 and 5 where one of my hinges is shown as applied to a door hung with vertically disposed 60 hinges, the elements and parts being practically identical with those shown in Figs. 1, 2 and 3. The keeper bracket 17 of Fig. 4 is similar to the keeper bracket 3 of Fig. 1, vertically disposed and having loop 4' provided

with a guide whereby the keeper bracket 17 65 becomes a socket having a vertical opening. The flattened arm of a hinge member seats in said vertical opening slidably whereby the slidably mounted element itself is displaced with relation to the casing, on functioning of the hinge. Lateral relief may be provided for, for example, by angular positioning of the bracket, or by widening of the socket laterally.

What I claim and desire to secure by Let- 75 ters Patent is:

1. A hinge comprising interacting coils, one a conical coil, and means of attaching the coils to the elements to be hinged.

2. A hinge comprising coils, one coil in- 80 teriorly engaging the other, and means for attaching the coils to the elements to be hinged.

3. A hinge comprising resilient coils, one coil interiorly and progressively engaging 85 the other, and means for attaching the coils to the elements to be hinged.

4. A hinge comprising spiral coiled springs having different diameters, the coils of one adapted to thread in the spiral groove 90 formed by the coils of the other, and means for attaching the springs to the elements to be hinged.

5. A hinge comprising spiral coiled springs having different diameters. the coils of one adapted to engage and thread in the 95 spiral groove formed by the coils of the other, and means for attaching the springs to the elements to be hinged.

6. A hinge comprising a bracket coil hav- 100 ing a bent end constituting a post plate, and a pin coil having a bent end for attachment thereof to a closure, the pin coil having a less diameter than the bracket coil and adapted to thread into the same.

7. A hinge for attaching a closure to a casing, comprising wires, one wire wound and constituting a spiral socket coil, an end thereof bent and flattened and constituting a post plate, and the other wire wound and constituting a conoidal pin coil, one end of 110 said wire lying in a tangent of said coil and constituting a means of attachment to a closure, the pin coil having a less maximum diameter than the socket coil by approxi- 115 mately half of the diameter of the socket coil wire, the pin coil cone-clutched in the socket coil, the arrangement adapted to the clutching of the flights of the pin coil by the flights of the socket coil on the opening 120 of the closure and the functioning of the torsional resistance of the pin coil towards retraction of the closure, for retention of a swinging element in a desired position.

In testimony whereof I affix my signature.

TANDY B. THURMAN.
